UNITED STATES PATENT OFFICE.

FRANK PERSIC, OF MINONK, ILLINOIS, ASSIGNOR OF ONE-HALF TO JACK TOMSICH, OF MINONK, ILLINOIS.

DESIGN FOR A BADGE.

No. 39,194.

Specification for Design.

Patented March 17, 1908.

Application filed January 20, 1908. Serial No. 411,822. Term of patent 7 years.

To all whom it may concern:

Be it known that I, FRANK PERSIC, a citizen of the United States, residing at Minonk, in the county of Woodford and the State of Illinois, have invented a new and original and ornamental Design for a Badge, of which the following is a specification, reference being had to accompanying drawing, forming a part thereof.

The figure is a view of a badge showing my design.

What I claim is:—

The ornamental design for a badge, as shown.

FRANK PERSIC.
